(57) **CLAIM**

The ornamental design for a kinesiology tape strip with release liner grid lines, as shown and described.

DESCRIPTION

FIG. 1 is a top perspective view of a kinesiology tape strip with release liner grid lines showing my new design;

FIG. 2 is a bottom perspective view thereof;

FIG. 3 is a top plan view thereof;

FIG. 4 is a bottom plan view thereof;

FIG. 5 is a first side elevational view thereof;

FIG. 6 is a second side elevational view thereof;

FIG. 7 is a first end elevational view thereof; and,

FIG. 8 is a second end elevational view thereof.

The portions illustrated in broken lines form no part of the claimed design.
